UNITED STATES PATENT OFFICE.

ADOLPH PEABODY AND NICHOLAS FORDE JOHNSON, OF LONDON,
ENGLAND.

FURNACE OF STEAM-BOILERS.

SPECIFICATION forming part of Letters Patent No. 696,840, dated April 1, 1902.

Application filed August 19, 1901. Serial No. 72,546. (No model.)

To all whom it may concern:

Be it known that we, ADOLPH PEABODY, a citizen of the United States, residing at the Hotel Cecil, Strand, London, and NICHOLAS FORDE JOHNSON, a subject of the King of England, residing at the Grove, Hammersmith, London, England, have invented certain new and useful Improvements in and Relating to the Furnaces of Steam-Boilers; and we do hereby declare the following to be a full, clear, and exact description of the invention, such as will enable others skilled in the art to which it appertains to make and use the same.

15 This invention relates to improvements in the furnaces of steam-boilers, the object being to insure the consumption of smoke and to economize fuel.

According to this invention we form an air-space at the lower part of the furnace by means of a metal plate, which we term the "channel-plate," fixed at a suitable height above the bottom of the flue by means of side pieces. This allows air to pass upward to the combustion-chamber, in which latter we place blocks of asbestos supported on hinged perforated plates placed immediately behind the furnace-bridge. We may employ asbestos alone, or in some cases we may prefer to mix fire-clay with the asbestos, or other substances having the property of absorbing and radiating a large amount of heat may be employed. A steam jet or nozzle, or a set of such jets or nozzles, is led into the air-chamber and comes beneath the plates which carry the blocks of asbestos. The purpose of this jet or set of jets is to clear away any dust from the top of the asbestos. It has been found in practice that without the use of a

30 cleansing spray or jet to clear the dust from the top of the asbestos blocks the said blocks rapidly clog and defeat the object of the invention. Another steam jet or jets is or are attached to the front end of the channel-plate in order to create an increased draft through the air-space.

We prefer to make the bridges of the furnace of iron.

In order that our said invention may be better understood, we will proceed to describe the same with reference to the drawings accompanying this specification, in which—

Figure 1 shows a longitudinal section of a Cornish boiler, the furnace of which is fitted with our improvements. Fig. 2 shows an end view of same. Fig. 3 shows the manner in which the plates which carry the asbestos blocks are hinged.

The same letters of reference denote the same parts in all the views.

a shows the channel-plate, forming the air-space *b* at the bottom of the furnace-flue *c*.

d shows perforated plates hinged at *e*, as shown at Fig. 3, and carrying asbestos blocks *f*.

g shows a jet or spray for cleaning the blocks *f*, and *h* shows a jet for inducing increased draft to the air-space *b*.

i shows iron bridges.

j shows steam-cocks to the jets *g* and *h*.

k shows the fire-bars.

By hinging the plates *d*, as shown, such plates may be raised to give ready access to the bottom of the furnace-flue for the purpose of cleaning.

In the case of other than Lancashire, Gal- 75 loway, and Cornish boilers the position of the secondary grate is changed to suit circumstances. For example, in the case of a tubular boiler we can place our secondary grate above the tubes and admit the air either through 80 the side or from the top of the boiler-setting.

The jets and steam-spray are arranged in a similar manner to that described for a Cornish boiler.

What we claim, and desire to secure by Letters Patent, is—

1. In a steam-boiler furnace, the combination of a main fire-grate, and a secondary grate adjacent thereto, comprising a plate covered with asbestos or like material; of 90 means for directing a blast of steam against the under side of said secondary grate for removing deposits therefrom, substantially as described.

2. In a steam-boiler furnace, the combination of a main fire-grate, and a secondary

grate adjacent thereto, comprising a plate covered with asbestos or like material; of a funnel-shaped nozzle located beneath said secondary grate adapted to direct a blast against the under side of said secondary grate for removing deposits therefrom, and means connected with the boiler of said furnace for

supplying steam to said nozzle, substantially as described.

ADOLPH PEABODY.

NICHOLAS FORDE JOHNSON.
